UNITED STATES PATENT OFFICE.

WALTER C. LINDEMANN, OF MILWAUKEE, WISCONSIN.

GAS STOVE.

Application filed February 17, 1925. Serial No. 9,749.

To all whom it may concern:

Be it known that I, WALTER C. LINDEMANN, a citizen of the United States, and a resident of the city of Milwaukee, in the county of Milwaukee, State of Wisconsin, have invented certain new and useful Improvements in Gas Stoves, of which the following is a specification.

The improvements relate to gas stoves, and more particularly to stoves of this character in which the stove top on which the cooking vessels are supported is designed to be wholly or partly closed after the manner of the ordinary solid fuel cook stove. Their objects are, among others, to provide for the proper supply, control and distribution of air to and in the burner box of such stoves, and the escape of such air and the products of combustion therefrom, and to provide means for the support of vessels of various sizes and character thereon. Other objects and advantages will be apparent to those familiar with devices of the character mentioned.

The improvements are illustrated in the accompanying drawings, which show an embodiment thereof, and in which

Figure 1 is a plan of a gas stove;

Figure 2 is a front view thereof; and

Figure 3 is a vertical section on the line 2—2 of Figure 1, looking in the direction indicated by the arrows in that figure, but showing a burner in full elevation.

The stove top 1 is provided with cooking holes and has removable plates 2 fitting and closing the same. The number of such openings may be as many as desired. In the middle portion of the top is a small opening provided with a cover 8, and this opening is adapted to receive the heat from a small burner (not shown) used for simmering or other like purposes.

The top has a depending flange 11 at its side edges and across its front, and is supported on a suitable stove frame 19, 19'.

The top also has annular stepped portions surrounding each cooking hole, as shown at 13, and prongs or fingers 3 preferably made integral therewith and extending partly across the opening. The lids or plates 2 are of ordinary form and have their flanged edges resting upon the stepped portions surrounding the openings so that the top when the plates are in position permits cooking utensils or other articles to be moved about freely thereon, as on the ordinary

nary range. The prongs or fingers 3 serve the purpose of the ordinary grate or spider commonly used on stoves employing fluid fuel, but by making them integral or practically integral with the stove top they are made more secure, and avoid some of the disadvantages resulting from the employment of loose grates. They also afford a support for vessels smaller than the openings, and permit them to be placed closer to the source of heat, and to a certain extent tend to direct the heat and products of combustion toward the flue 7 at the back of the stove. Their form is such that they do not interfere materially with the direct radiation of heat from the heating medium or the direct contact of the flame with the bottom of a vessel, when that is desired.

The burner 15 is located a suitable distance below the top, and directly beneath a cooking hole, as is usual, and this burner is supplied with a sufficient volume of air from below and above to properly support combustion and create an adequate body of heated fluid for cooking purposes by the air inlet at the front of the stove, which is open from a point well below the burner to a point a little above the same. Any number of burners may be provided, and in the preferred form one burner is located beneath each front cooking hole. Burners may be provided, however, in the rear and beneath the back cooking holes if desired, but as such burners add to the cost of the stove, and unless positioned at or below the level of the front burners will interfere to some extent with the movement of heated air and combustion products in the direction of the flue, they may be omitted without disadvantage. Moreover, as the burners at the front usually supply all the needs of ordinary cooking operations calling for direct heat, and the rear cooking holes may be employed at the same time for slower cooking or heating operations, they are dispensable.

A bracket 17 depending from the front flange 11 supports a gas supply pipe 12 which furnishes gas to the burner 15 through a cock 16 and a Bunsen mixer 14 of suitable type. Air for the mixers enters at the open front of the stove, and between and around the mixers to a point above the level of the burner top it enters the burner box freely. The burner is supported by the rod 18 extending across the stove.

Extending across the front of the stove in-

side its front face between the burners and the top is a baffle or guard 4, which has its upper edge slightly above the lower edge of the front flange 11 and its lower edge a little above the top of the burner. This guard is inclined inwardly from top to bottom, so that air entering the front of the stove at its level will pass upwardly around its upper edge and between it and the stove top and downwardly around its lower edge to a level above the base of the burner flames. In this manner the combustion space between the burners and the top is protected against drafts, and at the same time a supply of air is furnished to that space and to the burner flames. It will thus be seen that the burners are supplied with secondary air from above as well as from below from the air inlet extending across the front of the stove, and imperfect combustion and the giving off of noxious gases, which would result from an insufficient supply of air above the burners, guarded against. If, however, the pressure of heated air and other gases in the generating zone becomes too great the space above the guard 4 will permit the egress thereof toward the front, and thus maintain the proper balance between the interior of the burner box and the external atmosphere. The maintenance of this balance is also assisted by the perforations 10 at the back of the stove and in its rear wall, located on either side of the flue, and permitting the entrance of air or egress of heated air and combustion products to a limited extent. With these provisions it has been found that the burners may be burned at full flame with the top of the stove entirely closed without undesirable results, and perfect combustion maintained. The supply of secondary air to the burners from below and above and the restricted vents, arranged as above described are important to the attainment of the best results in a stove of this character, and not only prevent the undesirable results noted, but insure an even and avantageous distribution of the heat throughout the entire cooking area, substantially preventing the formation of eddies in the heated gases and the floating of the flames which would interfere seriously with combustion and with the efficiency of the stove. The perforations 10 also serve to prevent the choking of the burners by an obstruction of the flue, and prevent the interference with combustion and the giving out of obnoxious gases.

The bottom 6 of the burner box is removable, and acts as a "dirt tray", catching the drippings, particles of food and carbon from the portions of the stove above it. It also serves to limit the volume of air admitted to the lower part of the burner's box. The interior wall 9 extends upwardly from the bottom to about the level of the burner's bottom, and joins an upwardly inclined parti-

tion 5 extending to the rear wall of the stove. This construction directs air entering below the burners in an upward and rearward direction, so that there is a constant drift in the direction of the flue 7, and at the same time a slight concentration of heated air and combustion products as they approach the rear wall of the stove, tending to direct them upwardly through the rear cooking holes or against the plates when the holes are closed thereby.

The construction and arrangement of the parts is such that the stove as above described can be used with or without an oven, and in either use forms a separate and distinct unit. If an oven is provided it may be located beneath the burner box, or above it and provided with a separate flue or arranged to have its outlet lead into a common flue, according to the long established practice. The operation of the present stove, and of the oven, with either arrangement is not affected by the other.

What I claim is:

1. In a gas stove, a cooking top provided with cooking holes adapted to be closed, means for closing the same, a bottom member beneath said top and spaced therefrom, a stove frame comprising back and side members forming with said top and bottom a substantially unobstructed burner box and heat generating and distributing chamber extending from front to back of the stove, said box being open at its front, a burner located in the forward part of said space intermediate said top and bottom and in proximity to and below the top of the said open front, and having its top in free communication with said space and with the said top vertically and laterally, said open front admitting air directly to the top of and below said burner.

2. In a gas stove a cook top provided with cooking holes adapted to be closed, a stove bottom beneath said top and spaced therefrom, a stove frame comprising back and side members, forming with the said top and bottom, a burner box or heat generating chamber, said box being open at its front, a burner located in said space intermediate said top and bottom and in proximity to the said open front, said open front admitting air above and below the said burner, a baffle plate or guard extending across the front of the stove within the outer face thereof and between the said burner and the top, said baffle plate admitting air at different levels above the burner.

3. In a gas stove a cooking top provided with cooking holes adapted to be closed, a stove bottom beneath said top and spaced therefrom, a stove frame comprising back and side members, forming with the said top and bottom, a burner box or heat generating chamber, said box being open at its

- front, a burner located in said space intermediate said top and bottom and in proximity to the said open front and having its top exposed to the outer atmosphere through said open front, said open front admitting air above and below the said burner, a baffle plate or guard extending across the front of the stove within the outer face thereof and between the said burner and the top, said guard being spaced from the burner and the top and constructed and arranged to permit the passage of air over its upper edge and between it and the top and under its lower edge and between it and the burner.
4. In the construction specified in claim 1 the stove bottom having a vertically rising portion adjacent to the burner and extending upward from a point below the same to approximately the level thereof on the side removed from the open front.
5. In the construction specified in claim 1, the said bottom having an upwardly inclined portion extending from the forward part thereof to the rear.
6. In the construction specified in claim 1 the said stove frame having at its rear part a series of openings intermediate the said top and bottom.
7. In the construction specified in claim 1 the said stove frame having at its rear part a series of openings intermediate the said top and bottom, and said burner box having a baffle extending across its front portion between the burner and the top and admitting air at different levels above the burner.
8. In the construction specified in claim 1, the said stove frame having at its rear part a series of openings intermediate the said top and bottom, said burner box having a restricted opening at its front between the burner and its top.
9. In the construction specified in claim 1, the said stove frame having at its rear part a series of openings intermediate the said top and bottom, said burner box having a restricted air inlet at its front comprising a portion depending from the top and a baffle extending across its front and having a portion in lapped relation to the said depending portion.
10. In a gas stove a cooking top provided with front and back cooking holes adapted to be closed, a stove bottom beneath said top and spaced therefrom, a stove frame comprising back and side members, forming with the said top and bottom, a burner box or heat generating chamber, said box being open at its front, a burner located in said space intermediate said top and bottom beneath a front cooking hole and in proximity to the said open front, said chamber having an upper outlet at its back and back of a back cooking hole, and a portion of said bottom extending from a point below the top of the burner on an upward incline to the said outlet.
11. In the device specified in claim 10, the said bottom also having an upright portion back of the burner extending from a level below the burner and providing a restricted passage for air upward behind the burner.
12. In the construction specified in claim 1, horizontal finger-like members extending from the said cooking top toward the front and back of the stove over the said openings in a plane below the level of the said openings and forming a depressed grid for the support of a cooking vessel at said lower level, said horizontal members being spaced to provide passages between them for air passing from the front of the stove to the back.
13. In a gas stove the combination of a top, means for closing the top, a frame or casing supporting the top, a bottom extending across within said frame and forming with the same and the top a heat generating chamber, a burner located in said chamber intermediate its top and bottom and said chamber having a front opening extending above and below said burner, means for restricting the passage of air through said front opening above the burner, said chamber having a rear limited outlet opening, and restricted vents adjacent said opening, the construction and operation being such that an approximate balance between the heated gases in the chamber and the external atmosphere is maintained by the passage of air and other gases to and fro through said restricted front opening and rear opening and vents, and the heated gases are guided from front to back of the chamber.
14. In a device of the character described, a top, a bottom spaced therefrom and forming therewith a heat generating chamber, a burner located beneath the top and a baffle plate extending across the front of said chamber and spaced vertically from both the top and the burner.
15. A top having openings therein, means for closing said openings, a bottom spaced therefrom and forming therewith a heat generating chamber, a burner in said heat generating chamber spaced below said top, and means for admitting air to the top of said burner at one level, and beneath the said top at a higher level and for obstructing the entrance of air at an intermediate level.
- Witness my hand this 13th day of February, 1925, at the city of Milwaukee, in the county of Milwaukee, State of Wisconsin.

WALTER C. LINDEMANN.
